UNITED STATES PATENT OFFICE.

HEINRICH ERFLE, OF JENA, GERMANY, ASSIGNOR TO THE FIRM OF CARL ZEISS, OF JENA, GERMANY.

DOUBLE TELESCOPE.

Application filed August 13, 1921. Serial No. 492,113.

(GRANTED UNDER THE PROVISIONS OF THE ACT OF MARCH 3, 1921, 41 STAT L., 1813.)

To all whom it may concern:

Be it known that I, HEINRICH ERFLE, a citizen of the German Empire, residing at Jena, Germany, have invented a new and useful Double Telescope (for which I have filed an application in Germany, June 10, 1918), of which the following is a specification.

The present invention relates to double telescopes in which the ocular distance can be adapted to the interpupillary distance without a change of the position of the optical parts, lying in front of the oculars.

In the said telescopes, a sub-species of which is, e. g., described in the patent specification 947971, the ocular-axes do not generally coincide with the axes of the images produced by the objectives (hereafter briefly denoted as the image-axis), the position of the ocular-axes generally being such, that the ray pencils, entering parallelly to each other the objectives, form an angle with each other when emerging from the oculars. Hence, with the observation through a telescope of the said kind, the axes of the eyes must generally be forced into unnatural positions in which, with relaxed accommodation, they are inclined to each other, which will be particularly troublesome if the axes diverge in the direction of vision.

The object of the invention is to improve the said telescopes in such a way that also with any position of the oculars it will not be necessary to force the axes of the eyes into the said unnatural position. According to the invention the above object is attained by disposing behind each of the oculars a glass wedge rotatable about an axis, which is parallel to the optical axis of the respective ocular and by so coupling it to the latter that it is rotated when changing the distance apart of the oculars. By a suitable disposition and rotation of the wedges it can then be attained that the ray pencils axially entering the objectives are emerging from the telescope, to which in that case also the wedges are appertaining, parallel to each other or at least approximately parallel in any positions of the oculars.

In the annexed drawing Figs. 1 and 2 show the theoretical principles of the invention. Fig. 3 is a front view of a telescope according to the invention. Fig. 4 is a sec-

tion, Fig. 5 a front view of another telescope. Fig. 6 is partly a side view and partly a section of the telescope.

In which way the dependency of the rotation of the wedge upon the amount of the relative displacement of the oculars is to be chosen and in which manner the simultaneous rotation of the wedges and the relative displacement of the oculars may be realized, is illustrated hereafter with the aid of the Figs. 1 and 2 for oculars having collective effect, whereby it may be mentioned that the said explanations may also be applied accordingly to oculars having dispersive effect. In Fig. 1 the two image axes of a double telescope, which have the fixed distance apart l_0 be denoted by A^1-A^1 and A^2-A^2 . Let $B-B$ be the trace of the focal planes of the objectives, coinciding with the front focal planes of the oculars and $C-C$ the trace of the chief planes of the two oculars which, for simplicity's sake, are assumed to be very thin. The distance between the chief planes of the oculars and their focal planes is denoted by f . In addition, let the axes of the oculars coincide in a medium position with the corresponding image axes and, besides, it may be anticipated that, for adapting the ocular distance to the interpupillary distance, the axes are so moved in the plane of the image axes, that the two oculars are always lying symmetrically relatively to an intermediate plane, assumed to be between the image axes and vertical to the plane of the latter. With an optional distance l between the ocular axes, marked D^1-D^1 and D^2-D^2 , the direction of the ray pencils, axially entering the objectives, is given by the straight lines O^1-P^1 and O^2-P^2 after the ray pencils have traversed the oculars, and the angles of inclination which the said ray pencils, after having traversed the oculars, embrace with the image axes may thereby be approximately computed at

$$(1) \beta_1 = \beta_2 = \frac{l-l_0}{2f}$$

100

By the said angle the wedges, to be disposed behind the oculars according to the invention, would have to deflect again in the opposite sense in each particular case the said ray pencils in the plane of the image axes,

if the said pencils are to be directed parallelly by them. By denoting by α the deflexion which a ray of light undergoes in the main section of the wedge when hitting this wedge at a certain angle, e. g. such as 90° , the approximate amount of deflexion in the plane of the image axes, which may be denoted as lateral deflexion, will be

$$(2) \quad \alpha_s = \alpha \sin \varphi$$

according to a well-known law, if the main section of the wedge embraces with a plane, perpendicular to that of the image axes and containing one of the latter, the angle φ , whereby it is assumed that the main section itself runs parallel to one of the image axes or contains one of the latter. In accordance with the above it must then be

$$(3) \quad \alpha \sin \varphi = \frac{l - l_0}{2f}$$

and consequently the angle through which the wedge is to be rotated if the distance of the oculars be altered by the value $l - l_0$ will be

$$(3a) \quad \varphi = \arcsin \frac{l - l_0}{2\alpha f}$$

The simultaneous rotation of the wedge through the said angle with a rectilinear displacement of the oculars requires, however, a comparatively complicated actuating mechanism. The device will become simplified by so choosing the rotation of the wedge that in different positions of the oculars the angles φ are in the same proportion to each other as the differences $l - l_0$, corresponding to the said positions. As may be easily seen, the said device still affords within certain limits a comparatively good approximation to the law expressed by the equation 3a, so that such a device is also applicable. The position of the axes of rotation of the wedge is suitably so chosen that they coincide with the optical axes of the oculars.

If the adaptation of the ocular distance to the interpupillary distance be not effected by a displacement of the oculars parallel to the plane of the image axes but by a rotation of each of the oculars about an axis, lying outside its optical axis, as such is, e. g. the case in the device according to the above mentioned patent specification 947,971, a particularly good compensation of the relative inclination of the axial ray pencils, emerging from the oculars, can be attained with a simplified adjusting device by letting one of the axes of rotation of the wedge each coincide with one of the axes of rotation of the oculars and by choosing, contrary to the said patent specification, the position of the axes of rotation of the oculars in such a manner that the distance of the latter axes is equal to that of the image axes, in which case a symmetrical position of the oculars relative to an intermediate plane, assumed

to lie between the image axes and perpendicular to the plane of the latter, is again anticipated. In any positions of the oculars a complete compensation with the approximation, valid for the equation 3a, is then obtained as illustrated in detail in Fig. 2 of the drawing. In the said figure the image axes $A^1 - A^1$ and $A^2 - A^2$ are assumed to be perpendicular to the drawing plane, the distance apart of the said axes being again denoted by l_0 . Let M^1 and M^2 be the points of intersection of the axis of rotation for the oculars with the plane of the image axes. Let each of the axes of rotation of the oculars be at the distance r from the optical axis of the corresponding ocular, in the present case the disposition being so chosen that the cylindrical surfaces, on which the optical axes of the oculars are moving, surround the image axes. Moreover, let φ_1 be the angle, which the plane containing the axis of rotation of the left ocular and the optical axis of the latter, embraces with the plane containing the axis of rotation of the same ocular and the appertaining image axis, and φ_2 the corresponding angle of the right ocular. For any position of the oculars, in which their optical axes have the distance apart l , the relation

$$(4) \quad \sin \varphi_1 = \sin \varphi_2 = \sin \varphi = \frac{l - l_0}{2r}$$

then holds good. By so disposing the wedges behind the oculars that one each of the optical axes of the oculars and the appertaining axis of rotation of the ocular coincide in a principal section of the respective wedge, the angles φ_1 and φ_2 are simultaneously those angles which embrace at any one time the principal sections of the wedges with a plane, which is perpendicular to the plane containing the two image axes, and which contains one of the image axes. Hence, in the present case the condition expressed in the equation (3) is always entirely fulfilled, if

$$\alpha \frac{l - l_0}{2r} = \frac{l - l_0}{2f} \text{ or}$$

$$(5) \quad r = \alpha f,$$

i. e. if only to the radius r a certain value be given which depends on the deflexion of the wedge in the main section and the focal length of the ocular. In addition, it may be mentioned that in the case just dealt with, when computing the amount of inclination of the axial pencils to be removed by the wedges, the angles have to be taken into consideration which those straight lines embrace with the image axes which unite the points of intersection (P^1 and P^2 respectively) of the image axes with the front focal planes of the oculars and the projections of the corresponding optical centres (O^1 and O^2 respectively) of the

oculars, and that for the said angles the same relations take effect as for the angles β_1 and β_2 in the first mentioned case of the ocular displacement.

5 By rigidly connecting in the case just alluded to the wedges with the ocular tubes, for the simultaneous adaptation of the ocular distance to the interpupillary distance and the corresponding rotation of the 10 wedges, the same device can be used as hitherto necessary for the sole displacement of the oculars. A compensation of the relative inclinations of the ray pencils, axially entering the objectives, although being less 15 perfect than in the case just referred to, can naturally also be attained if the distance of the axis of rotation of the oculars be smaller or, as in the device according to the patent specification 947,971, larger than 20 the distance of the image axes.

In all cases referred to, the ray pencils observed are naturally only directed parallelly to each other by the wedges, whilst there still remains an inclination of the 25 said pencils relative to the height, which does not have, however, any troublesome effect, since no relative difference in the height of both images takes place.

In the first constructional example (Figs. 30 3 and 4) there are fixed parallelly to each other on a casing a , containing the two objectives b at a fixed distance apart c , three 35 guide bars d^1 , d^2 , d^3 , between which the two oculars are displaceably disposed parallelly to the plane of the image axes A^1 — A^1 and A^2 — A^2 . Each of the oculars consists of an eye lens e^1 and a collective lens e^2 , which are both fixed within a tube e . The said tube is so disposed within a socket f , that it can 40 be shifted within the latter in the direction of its axis but not be rotated relative to the socket, for which purpose it is provided with a pin e^3 , engaging in a slit f^1 of the socket f . The latter is in its turn 45 rotatably disposed within a second socket g , which is provided with a prismatic guide, paired with two of the guide bars d^1 , d^2 , d^3 . Besides, to each of the sockets f a toothed segment f^2 is rigidly connected which 50 engages in one of two racks h^1 and h^2 , both 55 screwed to the guide bar d^3 , and each of the sockets g is provided with two extensions g^1 and g^2 with a female thread. The arms of both oculars engage in a screw spindle i , 60 provided with a right and left-handed thread and rotatably disposed on the casing a . Finally, within each of the tubes e there is fastened an achromatic glass wedge e^4 between the eye lens and the eye cup of the 65 respective ocular.

The adaptation of the ocular distance to the interpupillary distance is effected in the present case by rotating the screw spindle i . Thereby, the sockets g and along with them the two oculars are either moved towards

each other or away from each other, according to the spindle being rotated in the one or the other direction. Owing to the motion of the sockets g , the toothed segments f^2 are rolling off the racks h^1 and h^2 , so that simultaneously with the displacement of the oculars a rotation of the same and thereby of the glass wedges e^4 takes place. The focussing of the oculars relative to sharpness of the image is effected by 70 axially displacing the tubes e in the socket f . 75

In the second constructional example (Figs. 5 and 6) on a casing k , containing the objectives, two guide rings l are fixed, in each of which a socket m is rotatably disposed which contains an axially shiftable but within the socket non-rotatable ocular-tube n with a collective lens n^1 , an eye lens n^2 and an achromatic wedge n^3 . Each of the sockets m carries a worm-wheel segment m^1 and with both segments there meshes a driving bar o , provided with both a right and a left-handed thread and rotatably disposed on the casing k . Besides, the guide rings l are eccentrically disposed relative 85 to openings p , which concentrically surround the image axes A^1 — A^1 and A^2 — A^2 whereby the margins of the openings act as 90 diaphragms of the field of view. The distance apart of the axes M^1 and M^2 of the 95 guide rings is chosen equal to the distance apart of the images axes.

By then giving the driving bar o a rotary motion, there is caused again beside a change of the distance apart of the oculars, a simultaneous rotation of the same and thereby of the wedges n^3 . The focussing of the oculars relative to sharpness of the image is also in this case effected again by 100 an axial displacement of the oculars within the sockets m . 105

I. claim:

1. In a double telescope two oculars, a glass wedge, rotatably disposed behind each of these oculars about an axis parallel to the ocular axis, means for changing the distance apart of the oculars, and means for coupling the said glass wedge to the respective ocular so as to be rotated when changing the distance apart of the oculars. 110

2. In a double telescope two oculars, each of which is rotatably disposed about an axis lying outside its optical axis, a rotatable glass wedge fitted behind each of these oculars, the axis of rotation of the said glass wedge coinciding with the axes of rotation of the oculars and the distance apart of the axes of rotation of the oculars being equal to that of the image axes of the telescope, and means for jointly rotating the oculars in 115 opposite direction. 120
